UNITED STATES PATENT OFFICE.

RUEL I. SHORT, OF LOS ANGELES, CALIFORNIA, ASSIGNOR TO ESSANDEE CORPORATION, OF LOS ANGELES, CALIFORNIA, A CORPORATION OF CALIFORNIA.

RADIATOR CAP.

Application filed November 2, 1921. Serial No. 512,250.

This invention relates to an automobile radiator and particularly pertains to a radiator cap thereof.

It is the particular object of the present invention to provide a radiator cap which may be permanently affixed to the filling spout of an automobile radiator and which is so designed as to permit the cap to be opened and closed without necessitating its removal from its permanent position, the cap being further fitted with means for permanently securing an indicator in position thereon.

The present invention contemplates the use of a fixed base providing means for securing it in position upon the spout of a radiator and to which base a rotatable cap member is secured, said cap being designed to provide a filling opening for the radiator when desired although at normal times the radiator spout is closed thereby, the cap being further fitted with means for permanently holding a gauge or indicator thereon.

The invention is illustrated, by way of example, in the accompanying drawings in which:

Figure 1 is a view in elevation showing the application of the present invention.

Fig. 2 is a view in plan showing the radiator cap with which the present invention is concerned.

Fig. 3 is a view in central, vertical section through the cap disclosing its details of construction and its application to a radiator spout.

Fig. 4 is a view in transverse section through the radiator cap as shown on the line 4—4 of Fig. 1.

Fig. 5 is a schematic view of another form of the invention as seen in perspective with the parts separated and broken away.

Referring more particularly to the drawings, 10 indicates the upper portion of an automobile radiator. Formed at the top of this radiator is a filling mouth or spout 11. This spout is preferably cylindrical and receives the base 12 of a radiator cap 13. The base constitutes an annular member 14 having a channel 15 formed in its lower face.

This channel receives the upper end of the spout 11. The inner wall 16 of the channel 15 is formed with a plurality of bosses 17 which have their longitudinal axes extended obliquely to the vertical center of the cap. These bosses are threaded to receive

set screws 18. The screws will therefore project outwardly and upwardly through the wall 16 and may be forced against the inner face of the radiator spout 11 to fasten the ring 14 to the spout. In order to increase the binding action it is preferable to point the ends of the screws so they may have a tendency to become imbedded in the metal of the spout. As shown in Fig. 4, three of these lock screws are provided although more might be used if desired.

The radiator cap comprises an inner fixed portion 19 and an outer rotatable portion 20. It is to be understood that the cap may be of any desired design or configuration although in the present instance the cap is shown as being frusto-conical. The fixed portion of the cap comprising an annular ring 21 which is threaded and sets over a complementary portion 22 of the base ring 14. A conical shell is formed as a continuation of this ring and is disposed there above. This shell has an upper end wall 23 for a purpose which will be hereinafter described. A filling opening 24 is formed through the side of the shell as clearly shown in Figs. 2 and 3. The fixed shell member 19 is permanently secured in position by pins 25 which pass through the threaded portions of the shell and the base.

The outer cap member 20 conforms to the inner cap 19 as shown in Fig. 3. This cap is also formed with an opening 24 which agrees in dimensions with the opening in the fixed cap member and which openings may be brought to register when desired. The outer cap has an upper end wall 26 fitting over the end wall 23 of the inner cap. A pivot pin 27 extends downwardly through central aligned openings in the two end walls 23 and 26. A set screw 28 secures the outer cap section to the pin 27 while it is free to rotate relative to the inner cap section. It will thus be evident that by rotation of the outer cap 20 its opening may be caused to register with the opening of the inner cap and that by further rotation of the inner cap may be entirely covered by the outer cap and the outer opening entirely closed by the wall of the inner cap.

In order to yieldably hold the two cap sections in close relation to each other a spring 29 is disposed around the pin 27 and beneath the wall 23 of the inner cap section. A nut 30 is threaded on to the pin and

presses upwardly against the spring to produce any desired tension thereon. The outer wall of this nut is downwardly tapered to permit a liquid to be easily poured through the filling opening 24 and into the spout. A set screw 31 fixes the nut in its adjusted position relative to pin 27. The upper end of the pin 27 is formed with a head 32 which is held against the end of the outer cap section 20 by pin 27. A packing washer 34 is interposed between the flange and the end of the cap to prevent leakage. In one form of the invention, as shown in Figs. 1 to 4 inclusive, a moto-meter is formed on the end of the pin although it will be understood that various other devices might be substituted therefor if desired. The cap may be rotated by two aligned handles 35 cast integral with the outer cap portion to facilitate in its rotation.

Reference being had to Fig. 5 of the drawing, it will be noted that the member 19 is not threaded on to the base but is formed with lugs 36. These lugs extend inwardly from diametrically opposite sides of the portion 21 and are formed with an upper inclined face co-operating with the lower face of lugs 37 extending from the portions 22 of the base. Attention is also directed to the fact that the lower marginal edge of the cap member 19 is inwardly tapered as indicated at 38. This taper setting over a portion 39 of the base 14. By this means the cap may be sealed against the base and will prevent leakage of water in the same manner as brought about by the thread used in the form of the invention shown in Fig. 3. In the form of the invention shown in Figs. 1 to 3 inclusive a suitable gauge is formed integral with the pin 27. This may not always be desired and when not required the pin indicated in Fig. 5 might be used without departing from the spirit of the invention.

45 In the operation of the present invention the cap structure is applied to a radiator by first positioning the ring 14 over and around the mouth of the spout 11 after which it is clamped in place by the screws 18. The inner cap portion 19 is then screwed on to the threaded lip of the base 12 after it is locked in position by the pins 25. The outer cap member 20 is then mounted over the member 19 and the pivot pin 27 is passed downwardly through the opening in the end wall 23 of the inner cap. It will be understood that it is preferable to secure the stem to the outer cap by its flange 32 before placing the cap member in position. As the pin is passed downwardly through the structure the spring 29 and the nut 30 may be placed thereon. The nut may then be tightened through the registering openings 24. The device is now ready for use and the openings may be alternately brought into

or out of register by rotation of the outer cap section.

It will thus be seen that the present invention provides means for permanently positioning a radiator cap over its spout and for holding a gauge in place and against removal.

While I have shown the preferred form of my invention as now known to me it will be understood that various changes in the combination, construction, and arrangement of the parts may be made by those skilled in the art without departing from the spirit of the invention as claimed.

Having thus described my invention, what I claim and desire to secure by Letters Patent is—

1. A cap for the filling spout of an automobile radiator comprising an apertured member having a flange extending down within the spout of the radiator, means on said flange to permanently secure said member to the spout and a rotatable member permanently fixed upon said apertured member for covering and uncovering the said aperture, the contacting faces of said members being inclined, and spring means for pressing said members together to form a tight closure.

2. A radiator cap comprising a base portion adapted to be mounted upon the spout of a radiator, a permanent cap member secured upon the base portion and formed with a filling opening therein, a flange on said member extending downwardly within the spout of the radiator, means on said flange to permanently secure said member to the spout, and a secondary cap member permanently connected to the first-mentioned cap member and rotatable with respect thereto, said secondary cap member being adapted to close the opening in the first-mentioned cap member when in one position and to expose the same when in another position, the contacting faces of said members being inclined, and spring means for pressing said members together to form a tight closure.

3. In combination with the spout of an automobile radiator, an annular base member, a flange on said member extending downwardly within the spout, means for fastening the flange in position within the radiator spout, a radiator cap fixed upon the base member and having a filling opening through the wall thereof and a closure plate rotatably disposed upon said cap and acting, when in one position, to close the opening therein, and, when in another position of rotation, to expose said opening, the contacting faces of said members being inclined, and spring means for pressing said members together to form a tight closure.

4. A radiator cap comprising an annular base member formed with a channel and

- into which the lip of a radiator spout may project, means carried by the inner wall of the channel for clamping it in position over said spout, a conical radiator cap fixed upon 5 said base and substantially closing the mouth of the spout, said cap having a filling opening through the wall thereof, a second rotatable cap conforming to the outer surface of the fixed cap and having an opening 10 through its wall which may be brought to register with the first mentioned opening, and pivot means for securing said second cap in its rotatable position upon the fixed cap.
- 15 5. A radiator cap comprising an annular base member formed with a channel and into which the lip of a radiator spout may pro-
- ject, means carried by the inner wall of the channel for clamping it in position over 20 said spout, a conical radiator cap fixed upon said base and substantially closing the mouth of the spout, said cap having a filling opening through the wall thereof, a second 25 rotatable cap conforming to the outer surface of the fixed cap and having an opening through its wall which may be brought to register with the first mentioned opening, and pivot means for securing said second cap in its rotatable position upon the 30 fixed cap and means for maintaining a tight joint between the adjacent surfaces of the two caps.

RUEL I. SHORT.
